UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,254,081.

Specification of Letters Patent. Patented Jan. 22, 1918.

Application filed July 5, 1916. Serial No. 107,540.

To all whom it may concern:

Be it known that I, FRANKLIN A. STEARN, a citizen of the United States, residing at Paterson, in the county of Passaic and State 5 of New Jersey, have invented certain new and useful Improvements in Telephone Systems, of which the following is a full, clear, concise, and exact description.

This invention relates to improvements in 10 telephone systems, of the type in which automatic switches are employed for distributing to a plurality of operators' positions the calls originated by the telephone lines of the exchange.

15 The invention more particularly has to do with a system in which the operation of the switches that extend the connections of the calling lines is governed by selection-controlling mechanism that is common both 20 to the switches and to the operators' positions to which the connections are to be extended. This selection-controlling mechanism is responsive to the engaged or unengaged condition of the various operators' 25 positions and acts to direct each call, as it is initiated, to an unengaged operator's position.

Heretofore it has been the practice to 30 keep selection-controlling mechanism of this sort constantly under the electrical control of all of the associated operators' positions so that it continually keeps established a path for the selection of an available operator's position by a call-extending switch. 35 It is the object of this invention so to organize the system that the selection-controlling mechanism is normally inert or quiescent and is made active to establish the selecting path only when one of the associated switches is in readiness to extend a 40 call. This effects a considerable saving of the current flow required in the operation of the system.

The preferred embodiment of the invention 45 is illustrated in the accompanying drawing, in which Figures 1, 2 and 3, taken together, and with Fig. 1 placed under Fig. 2, and Fig. 3 at the right of Fig. 2, show as much of a complete system as is necessary 50 for an understanding of the manner in which the system is organized and operates.

Referring to the drawings, the part of the complete system that is shown comprises a plurality of telephone lines extending from

stations A and B to a central office, two 55 operators' positions O and O' each of which is provided with cord circuits C for extending connections to called subscribers' lines, finder circuits F and F' terminating at one end in switches LF and LF' for connecting 60 the finder circuits with calling subscribers' lines and at the other end in cord selector switches CS and CS' for connecting the 65 finder circuits with the connecting circuits of the operators' positions, and selection 70 controlling apparatus SC for governing the selection of an idle operator's position by an actuated cord selector.

The cord selector switches CS and CS' are preferably of the type disclosed in 70 Patent 1,177,044 to J. L. McQuarrie, issued March 28, 1916. Each switch comprises a longitudinally movable shaft 1 carrying as many sets of brushes 2 as there are groups of stationary terminals to be engaged. To 75 move the shaft and its sets of brushes up, an extension at the lower end of the shaft is brought into engagement with the constantly rotating power member 3 by means of an idler wheel operated by the up-drive 80 magnet 34; and to move the shaft down, the extension is brought into engagement with the power member 4 by means of an idler wheel operated by the down-drive magnet 35.

Normally the brushes of each of the sets 2 85 are held apart so as to clear the associated terminals by means of a separating cam 5 located between the innermost brushes of the set. The cam 5 is rotatably mounted. and when rotated, releases the brushes and 90 permits them to engage the associated terminals. The tripping or releasing of the brushes is controlled by a number of trip-magnates 20, 21. Each of these when energized rotates an associated trip rod 6 95 that extends transversely to the switch shafts 1 and carries as many tripping yokes 7 as there are finder switches in the group. The trip rod in rotating brings all of its tripping yokes 7 into position to operate the 100 brush controlling cams 5 of the corresponding sets of brushes on all of the switches, so that whichever of the selector switches is caused to move up has that set of brushes tripped that corresponds with the particular 105 trip magnet 20, 21, that is at the time energized. When the selector switch that has been in use is returned to its normal posi-

tion, any of the associated controlling cams 5 that has been tripped is engaged and rotated in a reverse direction to separate its switch springs again and thus render them inactive.

Each of the cord selector switches has associated with it a commutator 8 which comprises a number of stationary commutator segments and a set of movable brushes 10 carried at the top of the switch shaft 1 and coöperating with the stationary segments. This commutator serves to make and break a number of controlling circuits in the various stages of the upward movement of the switch shaft.

The switches LF and LF', by means of which the finder circuits are brought into connection with the calling lines, may be of the same type as the cord selector switches, 20 in which case they are supplemented with controlling parts and circuits suitable for their operation; or they may be any other convenient type of switch, such as plugs and spring jacks for establishing connection between the finder circuits and the lines.

For controlling the circuits of the organization there are employed a number of sequence switches which are shown at different points and are designated 200, 300 30 and 400, respectively. These sequence switches may be of the type disclosed in Patent 1,127,808 issued February 9, 1915, to Reynolds and Baldwin. Each consists of an electro-magnetically controlled motor or 35 driving mechanism and a number of associated switch contacts. The switch contacts associated with each of the sequence switches are designated 201 to 216 inclusive; those associated with each of the sequence 40 switches 300 are designated 301 to 303 inclusive; and those associated with each of the sequence switches 400 are designated 401 to 414 inclusive. To each of the contacts associated with the various sequence switch 45 cams are applied certain numerals. These numerals in the case of the cams 201, 301 and 401 indicate the only positions of the associated sequence switch in which these particular contacts are open; the numerals applied to all of the other contacts of each 50 sequence switch indicate the only positions of the particular associated switch in which the associated contacts are closed.

The manner in which the system is organized will best be presented in connection with a description of the mode of its operation. It will be assumed that the subscriber at station A initiates a call. The removal of the telephone receiver from its switchhook closes a circuit that includes both windings of the line relay 12, the resting contacts of cutoff relay 11 and both limbs of the line. The line relay 12 is energized, and in closing its contact causes one of the 65 switches LF or LF' to extend the circuit

of the calling line to the associated finder circuit F or F'. This result may be brought about either directly by energizing the driving mechanism of one or the other of the switches if these are mechanically operated 70 switches, or indirectly by displaying a signal in response to which a distributing operator may insert a finder circuit plug in the spring-jack of the calling line if the switches are of that type. The method to 75 be preferred is illustrated in detail in Patent No. 1,247,770, issued to Samuel B. Williams, Jr., November 27, 1917.

Assuming that the circuit of the calling line has been extended to the finder circuit 80 F in one of the manners described, or in any other convenient and well-known way, and that the sequence switch 200 associated with the finder circuit has thereby been moved out of position 4, the apparatus proceeds to 85 select an idle operator's position and extend the circuit of the calling line to one of the connecting circuits with which the selected position is provided. When the sequence switch reaches position 5, in its movement 90 out of position 4, it closes a circuit that prepares the selection-controlling mechanism SC for coöperation with the cord selector switch in the immediately following stage of operation of the system. Normally the 95 selection-controlling mechanism is inert, and with no current flowing in any part of its circuit net-work. When the sequence switch 200 reaches position 5, a circuit is closed that extends from battery through 100 the winding of the relay 55 of the selection-controlling apparatus, conductor 71, sequence switch contact 215 (5 to 8) and to ground. The sequence switch 200 stops in position 6, in which position the circuit just 105 traced continues closed. When relay 55 of the selection-controlling apparatus attracts its armature as a result of the closure of the above traced circuit, it grounds a conductor that has a branch 81 extending to apparatus 110 associated with each of the operators' positions. At each operator's position there is a relay 92, the energization of which is effected by the grounding of the associated branch conductor 81, subject, however, to 115 the control of resting contacts of an associated relay 91 and of contacts 303 (1) of an associated sequence switch 300. The relay 91 and the sequence switch 300 are in 120 turn controlled by circuits that are responsive to the busy or idle condition of the associated position, as will hereinafter be explained. When the position is unengaged, both of the above mentioned contacts included in the energizing path for the relay 125 92 are closed. When the position is engaged and not in condition to have a call extended to it, one or the other or both of these contacts are open. Therefore, when the relay 55 operates and applies a ground to all of 130

- the branch conductors 81, only such of the relays 92 will be energized as are associated with positions where the operator is free to attend to an extended call.
- 5 Each of the operators' positions is represented in the selection-controlling apparatus SC, by a group of three relays 77, 93 and 94, and each also has an associated trip magnet, 20 for position O and 21 for position O'.
10 The relay 77 of each group is under the direct control of the associated position relay 92, the relay 92 in operating closing in its front contact and armature a circuit that extends from battery by way of conductor 82
15 and through the winding of the group relay 77 to ground. Thus, when relay 55 is operated as the result of the movement of a finder sequence switch 200 into position 5, it causes the operation of all of the group relays 77 that are associated with operators' positions which are in condition to receive an extended call.
- The path over which an actuated finder circuit controls the selection of an idle operator's position is under the joint control of the relays 77 of the corresponding groups. The energizing path is controlled in the armatures and back contacts of the relays 77 in series, each relay 77, in operating, disconnecting the conductor 141 from the relays 77 beyond it in the series and connecting the conductor with the relays 93 and 94 of the associated group. Thus, when the relay 55 acts to bring about the energization of all of the relays 77 associated with unengaged operators' positions, the energizing path by way of conductor 141 is prepared for the operation of the relays 93 and 94 corresponding to the first operator's position in the series that is unengaged. The energizing circuit is not closed, however, until the finder sequence switch 200 moves out of position 6.
- The movement of the finder sequence switch 200 out of position 6 depends upon the closure of a circuit that extends from battery through the left-hand winding of relay 30, sequence switch contact 209 (6) of the associated finder circuit, sequence switch contact 209 (9 to 4) of finder circuit F', conductor 76, outer armature and back contact of relay 54, right-hand back contact and armature of relay 61 to ground. The closure of this circuit is therefore dependent upon the condition of the sequence switches of the associated finder circuits and of the relays 54 and 61 that form part of the selection-controlling mechanism SC. When the relays 54 and 61 are inert and the sequence switches 60 of the other associated finder circuits are in any of their positions from 9 to 4 inclusive, the circuit traced above is completed and the relay 30 is energized. The relay 30, in operating, closes a circuit that extends from battery through the motor magnet and cam 202 (6) of the sequence switch 200, right-hand front contact and armature of relay 30, and sequence switch contacts 208 (18 to 14) and (2 to 7) to ground. The closure of this circuit moves the sequence switch out of position 6. A moment after the sequence switch 200 moves out of position 6, it closes a circuit that extends from battery through the left-hand armature and back contact of the relay 95 associated with the first operator's position in the series that happens at the time to be unengaged (assumed in the present case to be the relay 95 at position O), conductor 83, back contact and left-hand switch spring of the corresponding relay 93 80 of the selection-controlling apparatus, winding of that relay, winding of the associated relay 94, right-hand switch spring and resting contact of relay 93, front contact and armature of the associated relay 77, conductor 85 141, inner armature and front contact of relay 54 (which relay is energized by its inclusion in a branch of the path that is being traced), back contact and armature of relay 63, left-hand back contact and armature of relay 61, conductor 73, and finder sequence switch contact 215 (6 $\frac{1}{2}$ to 8) to ground. The closure of this circuit energizes relays 93 and 94, and relay 93, in operating, disconnects the windings of both relays 93 and 95 90 from the initial energizing path by way of the front contact of the associated relay 77 and the back contact of the operator's position relay 95, and includes them instead in a circuit that extends from battery by way 100 of the winding of the relay 95, conductor 84, left-hand armature and switch spring of relay 93, thence through the windings of both relays 93 and 94, the right-hand switch spring and armature of relay 93, and to 105 ground by way of the path already traced through the left-hand back contact and armature of relay 61 and conductor 73. The closure of this path maintains the energization of relays 93 and 94 independent of control by relay 77, and also causes the energization of the relay 95 of the selected position. Relay 94, in operating, closes in its right-hand front contact and armature the energizing circuit for the corresponding trip 110 magnet 20, thus setting the tripping mechanism for the release of the corresponding set of brushes when the cord selector moves up. In its left-hand front contact and armature, the relay 94 closes the energizing circuit of 115 the common relay 63 of the selection-controlling apparatus. This relay, in operating, closes a circuit that extends from battery through the left-hand winding of the finder circuit relay 30, sequence switch contact 210 120 (7), conductor 72, front contact and armature of relay 63, left-hand back contact and armature of relay 61 and to ground by way of conductor 73 and sequence switch contact 215 (6 $\frac{1}{2}$ to 8). Relay 30, in operating, closes 125

a circuit that extends from battery through the motor magnet and cam 202 (7) of the finder sequence switch, right-hand front contact and armature of relay 30 and sequence switch contacts 208 (18 to 14) and (2 to 7) to ground.

The closure of the above circuit moves the sequence switch 200 from position 7 to position 8. In position 8, a circuit is closed 10 that extends from battery through the up-drive magnet 34 of the associated cord selector switch CS, conductor 89, sequence switch contact 207 (8 to 9), right-hand front contact and armature of relay 30, and sequence switch contact 215 (8 to 9) to ground. The relay 30 is at this time held energized as a result of a locking circuit by way of its right-hand winding that was completed when the relay was operated in position 7 15 of the sequence switch by the actuation of relay 63 of the selection-controlling apparatus, as previously described. This locking circuit extends from battery through sequence switch contacts 205 (2 to 9), right-hand winding of relay 30, sequence switch contacts 216 (7 to 9) and (2 to 9), left-hand front contact and armature of relay 30, and to ground by way of the armature and back contact of relay 37. The up-drive magnet 34 remains energized and the upward movement of the cord selector CS continues as long as the relay 30 remains energized; and the continued energization of the relay 30 is under the control of relay 37 which governs the locking circuit of relay 30.

At the outset of the upward movement of the cord selector CS, the tripping levers 5 of all of the sets of brushes come into position to be engaged by their corresponding 40 tripping yokes 7; and as it is the trip magnet 20 that in the present instance is energized, the set of brushes 2 is tripped and made active that is adapted to engage the terminals of connecting circuits leading to 45 the corresponding operator's position O. Immediately after the brush-tripping point is passed, a circuit is closed that releases the selection-controlling apparatus and moves the finder circuit sequence switch into 50 its next position. This circuit extends from battery through the winding of relay 61, conductor 74, sequence switch contact 211 (7 $\frac{1}{2}$ to 8), conductor 80 and segment K of the cord selector commutator and corresponding brush to ground. In operating, the relay 61 closes a locking circuit for itself by way of its left-hand front contact and armature, conductor 73 and sequence switch contact 215 (6 $\frac{1}{2}$ to 8) to ground. It also 55 opens, in its left-hand armature and back contact, the connection of the conductor 73 with the operated group relays 93 and 94 and the position relay 95 of the O operator's position, which connection up to this time 60 had been maintaining these relays energized.

The above mentioned relays therefore become inert, deenergize the associated trip magnet 20, and restore the circuits of the selection-controlling apparatus to their normal condition. The relay 61, in operating, 70 also closes the circuit that extends from battery through the motor magnet and cam 204 (8) of the finder circuit sequence switch, conductor 75, and right-hand front contact and armature of relay 61 to ground. The 75 closure of this circuit moves the finder circuit sequence switch from position 8 to position 9. As it moves out of position 8, the finder sequence switch opens the locking circuit of relay 61, and, in reaching position 80 9, it closes in sequence switch contact 209 (9 to 4) the series path which is employed for moving out of position 6 the sequence switch of any of the finder circuits. As ground has been reapplied to this series 85 path by way of conductor 76 and resting contacts of relays 54 and 61 in the release of the last mentioned relay at the completion of the selecting operation, the selection-controlling apparatus SC is again available for 90 the use of any finder circuit that is ready to extend a call.

After the cord selector switch CS passes the brush-tripping position, it continues its upward movement until the brushes are 95 stopped by engaging the terminals of one of the connecting circuits that is idle or unengaged. The idle or busy condition of the connecting circuit is indicated by the presence or absence of ground on the test 100 terminal 118 of each connecting circuit. When the brushes engage the terminals of an idle connecting circuit, a path for the flow of current is completed from battery through the winding of the relay 37, sequence switch contacts 206 (8 to 9), conductor 99, brush 114, test terminal 118, conductor 88, listening key sequence switch contact 406 (1) and back contact and armature of relay 420 to ground. Relay 37 thereupon attracts its armature and opens the 105 previously traced locking circuit that has been holding relay 30 energized. Relay 30, in releasing its armatures, opens in its right-hand front contact and armature, the energizing circuit for the up-drive magnet 34, thus stopping the brushes of the cord selector switch in engagement with the terminals of the selected connecting circuit. In engaging its back contact, the right-hand 110 armature of relay 30 closes an energizing circuit for the motor magnet of the finder sequence switch, by way of cam 202 (9) and cam 215 (8 to 9), which moves the sequence switch 200 out of position 9. The finder 115 sequence switch then continues to move until it reaches position 14, where the talking circuit is completed in cams 213 and 214.

An instant after the finder sequence switch leaves position 9, it closes a circuit 120

that extends from battery through the winding of relay 421 of the connecting circuit, listening key sequence switch contacts 407 (1), left-hand back contact and armature of relay 422, conductor 87, cord selector switch terminal 117 and corresponding brush 113, conductor 98, and finder sequence switch contacts 205 (9 $\frac{1}{4}$ to 14) and (9 $\frac{1}{4}$ to 11) to ground. Relay 421, in operating, closes a locking circuit for itself that extends by way of its left-hand front contact and armature, and sequence switch contact 405 (1 to 6) to ground. Relay 421 also closes a circuit that extends from battery through the motor magnet and cam 403 (1) of the listening key sequence switch and right-hand front contact and armature of relay 421 to ground. The closure of this circuit causes the listening key sequence switch 20 to move out of position 1, and in doing so, to open the test conductor 88 in sequence switch contact 406 (1), thus making the connecting circuit test busy, and also to open in sequence switch contacts 407 (1) the path over which the relay 421 was first energized.

Associated with relay 421 is a relay 423 which is energized and locked up over the same path as relay 421. Relay 423, in operating, closes a circuit that extends from battery through the winding of relay 422 and front contact and armature of relay 423 to ground. As a result, relay 422, prior to the moving of listening key sequence switch out of position 1, has disconnected conductor 87 from connection with battery by way of sequence switch contact 407 (1) and the windings of relays 421 and 423, and has connected it with an alternative path to battery by way of the left-hand front contact of relay 422 and the device 424. When the listening key sequence switch reaches position 2, an additional path to ground for holding the relay 422 energized is closed by way of sequence switch contact 412 (2 to 7).

When the listening key sequence switch 400 is moved out of position 1, in the manner described above, it continues its movement until it reaches position 7. In position 7, the cams 408, 409, 410 and 411 of the listening key sequence switch interrupt the talking strands of the connecting circuit and include between their severed ends a loop that has connection by way of conductors 135 and 136 with the operator's telephone set 147. This puts the operator in communication with the calling subscriber. Upon learning the number of the line that is wanted, the operator may complete the connection by inserting the calling plug 425, in which, in the present instance, the connecting circuit is represented as terminating, into the spring jack 14 $\frac{1}{2}$ of the called subscriber's line. Instead of a plug and spring jack, any other of the well-known switching devices or mechanisms for estab-

lishing connection between a connecting circuit and a telephone line may obviously be employed. In the present instance, the connection-extending means is represented as a cord circuit provided with a repeating coil 426, answering and calling supervisory relays 427 and 428, respectively, and a switch 429 for applying ringing current from the source 430 to ring the bell at the called subscriber's station D. As all of these parts 70 may have their usual functions and may operate in the usual way, a description of them and of the exact manner in which the cord circuit is organized is thought to be unnecessary.

When the calling plug 425 is inserted in the called line spring-jack, an energizing circuit is completed that includes serially the windings of the connecting cord relays 420 and 431 and the cut-off relay 11 $\frac{1}{2}$ of the 85 called line. The cut-off relay 11 $\frac{1}{2}$ may have its usual functions of disconnecting the line relay 12 $\frac{1}{2}$, thus depriving the line of control over the calling apparatus. The relay 420, in operating, interrupts, at another point 90 the path to ground of the test conductor 88. The relay 431, in its back contact, breaks the connection of the tip of the plug with a conductor 133, which extends to the operator's telephone apparatus and is used in 95 connection with testing the called line before inserting the plug, and, in its front contact, closes the tip strand of the connecting circuit for talking purposes.

After the connection between the calling 100 line and the called line has been established, the operator may disconnect her telephone apparatus from the connecting circuit by pressing the key 432. This closes a circuit that extends from battery through the motor magnet and cam 402 (7) of the listening key sequence switch 400, and to ground by way of the closed contact of the key 432. The switch 433 is closed when the calling 105 plug 425 is inserted, so that when the listening key sequence switch moves out of position 7 as result of pressing key 432, the energization of relay 422 is maintained by a path that extends through the right-hand front contact and armature of the relay and 110 to ground by way of the closed contacts of switch 433.

The termination of the conversation between the subscribers is indicated in the 115 usual way by signals displayed when the 120 supervisory relays 427 and 428 become inert, and disconnection is effected by opening switch 433. This interrupts the energizing circuit of relay 422, and that relay, in releasing its armatures, breaks the connection 125 of conductor 87 with battery by way of the device 424. When current ceases to flow through conductor 87, the relay 30 of the finder circuit, which has been included in the path of current flow by way of con- 130

ductors 87, 98, 50 and 53 and finder sequence switch cams 205 and 212, releases its armatures. This closes the circuit from battery through motor magnet and cam 202 5 (8 to 14) of the finder sequence switch, left-hand back contact and armature of relay 30 and armature and back contact of relay 37 to ground. This moves the finder circuit sequence switch from position 14 10 to position 15, where a circuit is closed from battery through the motor magnet and cam 202 (15) of sequence switch 200, right-hand back contact and armature of relay 30, and cam 215 (15) to ground. 15 When the finder sequence switch reaches position 16 as the result of the closure of the above circuit, a circuit is completed that directly or indirectly may cause the brushes of the switch LF to be disconnected 20 from the terminals of the calling line. When this disconnection is effected, a circuit may be completed that extends from battery through the motor magnet and cam 204 (16) of the finder sequence switch to 25 ground. This moves the finder sequence switch 200 to position 17, in which position a circuit is closed that extends from battery through the down-drive magnet 35 of the cord selector switch CS, conductor 90 30 and finder sequence switch contact 215 (17) to ground. This causes the return of the cord selector switch. When the switch reaches its normal position, it closes a circuit that extends from battery through the 35 motor magnet and cam 204 (17) of the finder sequence switch, conductor 31 and segment Y of the cord selector commutator and corresponding brush to ground. This causes the return of the finder sequence 40 switch 200 to its normal or 1 position; and from this position it is later moved through its 1, 2 and 3 positions by means of circuits controlled in finder sequence switch cams 202 and 203. These circuits are not concerned 45 with the present invention and need not be described.

When the switch 433 is opened to release the connection, a switch 434 is operated to complete a circuit that extends from battery 50 through the motor magnet and cam 402 (15) of the listening key sequence switch and closed contacts of switch 434 to ground. The closure of this circuit moves the listening key sequence switch from its listening 55 out position 15 to its normal position 1. This restores the connecting circuit to its normal condition and renders it again available for selection by a cord selector.

As has been explained hereinbefore, the 60 selection-controlling apparatus SC includes a relay 77 for each of the operators' positions to which the selection-controlling apparatus is adapted to cause the cord selector switches to extend calls; and unless the cor- 65 responding relay 77 is energized, a cord

selector that is extending a call cannot select that operator's position. The energization of relay 77 is under the control of the associated relay 92 at the corresponding operator's position; and the energization of the relay 70 92, by the operation of the common relay 55 when a selector switch is ready to extend the call, is in turn under the control of switches that are responsive to the engaged or unengaged condition of the corresponding operator's position. The above mentioned switches, in the present instance are the cam 75 303 of the operator's sequence switch 300 and the armature and resting contact of the relay 91. One or the other or both of these 80 switches is operated to open the energizing path of the relay 92 whenever the operator's position is unavailable for receiving calls.

Thus, when the operator's position has been selected by one of the call extending 85 circuits, the position is rendered inaccessible to other call extending means. When the position is selected, the relay 95 is operated in a manner previously described. In operating, the relay 95 closes a circuit that extends from battery through the motor magnet and cam 302 (1) of the operator's sequence switch, right-hand front contact and armature of relay 95, and right-hand front contact and armature of relay 125 to ground. 90 The relay 125 at this time is operated, as its energizing path is completed by way of local contacts 127 of the operator's telephone jack 126, which contacts are closed when the operator is at her position and has her telephone plug inserted in the telephone jack. 95 As a result of the closure of the circuit traced above, the operator's sequence switch 300 is moved out of position 1, thus opening the energizing path of relay 92 in sequence 100 switch contact 303 (1) and making the position unselectable.

The next resting position of the operator's telephone sequence switch 300 is position 4; but as relay 125 is energized, the motor magnet has an energizing circuit in this position by way of sequence switch contact 302 (4) and the left-hand front contact and armature of relay 125 to ground, and, consequently, the sequence switch moves on to its 110 next resting position, 17. The sequence switch remains in position 17, keeping the operator's position unselectable, until at a later stage in the operation, the switch 192 is operated in any suitable manner, to close its 115 contacts. At this time, a circuit is closed that extends from battery through the motor magnet and cam 302 (17) of the operator's telephone sequence switch and closed contacts of switch 192 to ground. The closure 120 of this circuit permits the sequence switch to move from position 17 to position 1, thus rendering the operator's position again available for receiving calls.

When the operator's telephone set is con- 125

nected with one of the connecting circuits, the corresponding position is also rendered unselectable. This is effected through the medium of the relay 91. When the listening 5 key sequence switch 400 of any of the connecting circuits of the operator's position is moved to position 7 to bring the operator's telephone set into connection with the corresponding circuit, an energizing path is completed 10 that extends from battery through the winding of relay 91, conductor 137, and listening key sequence switch contact 404 (2 to 9) to ground. The completion of this circuit causes the relay 91 to attract its 15 armature and interrupt the path over which relay 92 is adapted to be energized, thus preventing the operation of the associated selection-controlling relay 77.

The removal of the telephone plug from 20 the operator's telephone jack 126 when the operator leaves her position, also renders the position unselectable. When the plug is removed, the breaking of the local contact 127 causes relay 125 to become inert and release 25 its armatures. This closes a circuit that extends from battery through the motor magnet and cam 302 (1) of the operator's telephone sequence switch 300, and to ground by way of the left-hand back contact and armature of relay 125. In moving out of position 30 1 as the result of the closure of this circuit, the sequence switch interrupts the energizing path for the relay 92 in sequence switch contact 303 (1), thus preventing the 35 operation of the corresponding selection-controlling relay 77 when a connection is to be extended.

The particular system herein illustrated and described includes several features that 40 are the inventions of others and that are disclosed and claimed in other copending applications. This is in order that a clear understanding of the organization and mode of operation of the preferred embodiment of 45 the present invention may be had, but with no intention of claiming such other features.

What is claimed is:

1. The combination with a switch having 50 a plurality of groups of stationary terminals and adapted for group and individual terminal selection, of a plurality of operators' positions, a group of connecting circuits at each position, each of said groups 55 of circuits having connection with a corresponding group of switch terminals, selection-controlling apparatus controlling the group-selecting operation of said switch, a relay at each operator's position, said relays 60 coöoperating in the control of said selection-controlling apparatus, a normally open energizing circuit for each relay, and means actuated in initiating a call for closing said energizing circuits of the relays at unengaged operators' positions.
2. The combination with a plurality of operators' positions, of a group of connecting circuits at each position, a switch for extending a call to any of the circuits of any of said groups, apparatus for controlling 70 the group-selecting operation of said switch, and means made active in initiating a call for placing said apparatus under the control of said operators' positions.
3. The combination with a plurality of operators' positions, of a switch for extending calls thereto, said switch having a normally inactive brush for each operator's position, a tripping magnet for each brush adapted when energized to make the corresponding brush active, apparatus for controlling the selection of a particular one of said trip magnets for energization, means made active upon the initiation of a call for placing said apparatus under the control 85 of said operators' positions, and means for energizing the selected tripping magnet.
4. The combination with a plurality of operators' positions, of a group of connecting circuits at each position, a switch for extending a call to any connecting circuit of any of said positions, apparatus controlling the group selection of said switch, a switch at each operator's position responsive to the busy or idle condition thereof, and means made active in initiating a call for placing said apparatus under the control of 90 said operators' position switches.
5. The combination with a plurality of operators' positions, of a switch for selecting 100 the same to extend calls thereto, a corresponding plurality of magnets associated with said switch, means actuated by each of said magnets when energized to cause said switch to extend a call to the corresponding 105 operator's position, means made operative in initiating a call for selecting one of said magnets for energization, and means made operative thereafter for energizing said selected magnet.
6. The combination with a switch having 110 a plurality of groups of terminals and a corresponding plurality of normally inactive brushes, of a magnet for each brush, means actuated by each of said magnets when energized for rendering active the corresponding brush, a circuit terminating in said brushes, groups of circuits connected respectively with said groups of terminals, means under the control of said first-mentioned circuit for causing the selection of one of said magnets for energization, and means made operative thereafter for energizing said selected magnet.
7. The combination with a call-extending 125 switch having a plurality of groups of terminals and a corresponding plurality of normally inactive brushes, of a magnet for each brush, means operated in the energization of each magnet for making the circuit 130

sponding brush active, a plurality of operators' positions each having a group of connecting circuits terminating on a corresponding group of terminals on said switch, switching mechanism associated with each operator's position and responsive to the engaged or unengaged condition thereof, normally inactive selection-controlling apparatus, means actuated in initiating a call for placing said apparatus under the control of

said switching mechanisms, and energizing circuits for said magnets controlled by said apparatus, said apparatus acting to cause the energization of a single one of the magnets corresponding with an operator's position that at the time is unengaged. 15

In witness whereof, I hereunto subscribe my name this 3rd day of July, A. D., 1916.

FRANKLIN A. STEARN.
